UNITED STATES PATENT OFFICE.

GEORGE W. HEENE, OF CLEVELAND, OHIO.

BLANK.

SPECIFICATION forming part of Letters Patent No. 768,124, dated August 23, 1904.

Application filed February 4, 1904. Serial No. 192,028. (No model.)

To all whom it may concern:

Be it known that I, GEORGE W. HEENE, a citizen of the United States, residing at Cleveland, in the county of Cuyahoga and State of Ohio, have invented certain new and useful Improvements in Blanks; and I do hereby declare the following to be a full, clear, and exact description of the invention, such as will enable others skilled in the art to which it pertains to make and use the same.

My invention relates to blanks for stamping-machines, such as are adapted to have letters or characters formed in relief thereon.

The objects of my invention are, first, to supply a blank that is reversible as to the side to be presented to the die or matrix, and, second, to form the blank so that the impressing of the die will form the letter full in relief.

My invention consists in the peculiar construction of the blank whereby the above objects are attained, all of which will hereinafter fully appear, and be particularly pointed out in the claims.

In the drawings, Figure 1 is a view illustrating a blank subject to and being operated upon by a die, illustrating the peculiar adaptation of the blank for machines of this type. Fig. 2 is a cross-sectional view of the blank, illustrating the construction or formation of the same more clearly and partly stamped, so as to throw the letters in relief. Fig. 3 is an isometric view of a blank.

In forming the blank, which is made of ductile metal, and preferably aluminium, I form the same disk shape or circular in plan, either with a finished edge, a fancy edge, or with a plain edge A and with a plain or fancy center B. This center may be blank and of fancy form, or it may have a suitable motto or advertisement thereon.

The bead C is an important feature of the blank, as it is this portion that is operated upon by the machinery. In my application for patent, filed June 14, 1902, Serial No. 111,708

I show a machine for which this blank is adapted. It is essential that this bead C of the blank should be uniform in every respect and annular in plan and concentric with the edge of the blank and that it should project from the face of the blank in annular ring form, leaving material enough to form characters in relief when operated upon by the machine.

I have found that in making the blanks it is preferable to form the blank with annular beads C on both faces and in identically the same relation to the blank. The object of this is to prevent mistakes in feeding the disks to the hopper or feeder and to always present the blank so that it will be operated upon rightly regardless of the face presented. In machines into which the blanks are fed by hopper mistakes are oftentimes made by ignorant operators, and hence the necessity of a construction which cannot be improperly fed. Also by forming the bead C out from the face and concentric with the edge a perfect action and result is attained, and every disk operated upon will turn out perfect as far as the lettering is concerned.

What I claim is—

1. A blank formed on one of its faces at a point within the bounds thereof with a raised annular bead, said bead having a flat upper face, substantially as and for the purposes specified.

2. A blank having its two substantially flat faces formed with oppositely-disposed raised beads, said beads being equidistantly spaced from the edges of the blank at all points, the outer faces of said beads being flat, substantially as and for the purposes specified.

Signed at Cleveland, in the county of Cuyahoga and State of Ohio.

GEORGE W. HEENE.
